(57) **CLAIM**

The ornamental design for a bedside patient monitor as shown and described.

DESCRIPTION

FIG. 1 is a front perspective view of a bedside patient monitor, showing the new design;
FIG. 2 is a right side view of the bedside patient monitor;
FIG. 3 is a front view of the bedside patient monitor;
FIG. 4 is a left side view of the bedside patient monitor;
FIG. 5 is a top view of the bedside patient monitor;
FIG. 6 is a bottom view of the bedside patient monitor; and,
FIG. 7 is a back view of the bedside patient monitor.
The broken lines, the areas within them, and the areas bounded by broken lines and solid lines, depict portions of the bedside patient monitor that form no part of the claimed design.
